DRAINAGE TUBE

Ward R. Smith, Dayton, Ohio

Application October 4, 1934, Serial No. 746,801

20 Claims.

(Cl. 27—24)

This invention relates to embalmers' instruments and more particularly to a drainage tube for removal of blood having provision for clearing the tube of blood clots or other obstructions.

5 After death the arteries are found empty and the blood supply collected in the veins. To prevent discoloration and distention or "puffing" while a preservative embalming fluid is being injected into the arteries, it is customary to withdraw the contents of the veins.

10 For this purpose an elongated tube is introduced into one of the larger and easily accessible veins. Usually the axillary vein or its continuation, the basilic vein, is selected, which when the arm is extended, is substantially aligned with the subclavian vein permitting the drainage tube to be introduced to approximately the juncture with the internal jugular vein where the vessels are materially larger than the diameter of the tube and afford ample clearance for free blood 15 flow.

20 While for the most part the blood continues fluid and flows freely, occasionally through separation or disintegration jelly-like clots and stringy masses of fibrin are formed which tend to clog the entrance to the drainage tube and arrest the blood flow. Various devices have heretofore been proposed for dislodging such obstructions and for cutting the clot or mass. However, such appliances afford but temporary relief 25 and the dislodged material again collects at the tube inlet.

25 The purpose of the present invention is to enable the removal of such obstructing masses by initially distending the blood vessel about the intake to the tube and so release any compacted mass of material, and thereafter snare the obstructing material for positive extraction through the tube.

30 The object of the invention is to improve the construction as well as the means and mode of operation of drainage tubes whereby they may not only be economically manufactured, but will be more efficient in use, easily operated and cleared and unlikely to get out of repair.

35 A further object of the invention is to provide manually operable means for distending a blood vessel about the entrance to the drainage tube.

40 A further object of the invention is to provide means for positively engaging and withdrawing obstructing masses of material.

45 A further object of the invention is to provide a snare operable through the tube for engaging clots or stringy masses.

50 A further object of the invention is to provide

a dislodging and engaging means subject to manual manipulation.

A further object is to provide means for clearing lateral inlet orifices in the drainage tube.

5 A further object of the invention is to provide an expandible and contractable operating member subject to manual operation and control.

10 A further object of the invention is to provide an instrument possessing the advantageous features of construction and meritorious characteristics herein mentioned.

15 With the above primary and other incidental objects in view, as will more fully appear in the specification, the invention consists of the features of construction, the parts and combinations 15 thereof, and the mode of operation, or their equivalents, as hereinafter described and set forth in the claims.

20 In the drawing wherein is shown the preferred but obviously not necessarily the only form of embodiment of the invention, Fig. 1 is a side elevation of the assembled drainage tube forming the subject matter hereof. Fig. 2 is an enlarged perspective view of the intake end of the tube with the snare removed. Fig. 3 is an enlarged perspective view of the snare removed from the tube. Fig. 4 is an enlarged perspective view of the intake end of the tube with the snare in expanded relation thereto. Fig. 5 is an enlarged sectional view of a portion of the tube 30 with the snare therein. Fig. 6 is a detail sectional view, showing the snare blades expanded.

25 Like parts are indicated by similar characters of reference throughout the several views.

35 The use of a drainage tube for the present purpose is quite old and well known. For illustrative purposes but with no intent to unduly limit the application or scope of the invention there is shown in the drawing a drainage tube of the type shown in patent to Andrews No. 954,494 of 40 April 12, 1910, comprising an elongated conduit portion 1 having a lateral discharge branch conduit 2. The main tubular conduit 1 is closed at its outer end by a screw threaded cap or head 3 enclosing a sealing gasket. The cap and gasket 45 are perforated for accommodation of a reciprocating snare stem as hereinafter described. The tubular conduit is open at its intake terminal where it has a slightly contracted orifice 4, about which is formed a thrust seat or annular abutment 5 adjacent to the open terminal of the tube, and is further longitudinally slotted at 6. Such lateral intake slots 6 are relatively long and comparatively wide. Ordinarily four such slots are 50 equally spaced about the periphery of the tube 55

1 alternating with unslotted portions of substantially equal extent. It will be understood, however, that a greater or lesser number of slots to accommodate corresponding snare blades may be 5 provided.

Extending axially within the tube 1 is a reciprocatory stem or rod 7 projecting beyond the terminal cap 3 where it carries a knob 8. At its 10 opposite end the reciprocatory rod carries a cage like head 9 comprising a group of longitudinally disposed laterally spaced flexible blades or wires 10 interconnected at one end to the reciprocatory stem or rod 7 and collectively attached at their 15 opposite end to a thrust head 11. The thrust head 11 is preferably tapered and adapted to extend beyond the end of the tube through the terminal opening 4 when the rod 7 is in its advanced position. In such relation the periphery of the thrust head 11 will have contact engagement 20 with the annular abutment or seat about the terminal opening 4 while the cage like group of flexible snare members lies within the slotted portion of the tube with such flexible members 10 in registry with the respective slots 6. In this 25 condition the tube can be introduced into the vein, which is facilitated by the tapered thrust head 11 projecting beyond the end of the tube and serving as a pilot. The rod 7 is then retracted by the knob 8 until the expandable head 30 9 is beyond the outlet branch 2 of the tube which is connected by rubber tubing with a receiver, thus permitting free drainage of blood.

When, however, the blood flow is interrupted 35 by accumulation of fibrin or clots about the intake orifices of the tube, the rod is advanced in the tube and rotatively adjusted until the flexible blades or wires 10 are in registry with the lateral slots 6, and the thrust head 11 is seated against the annular abutment seat 5. Then by applying 40 pressure to the rod knob 8 the cage like head is expanded by longitudinal compression causing the blades or wires 10, as the case may be, to bow outward through the lateral slots 6. The distension of the members 10 not only serves to clear 45 the slots, by dislodging any deposits which may be clogging the slots, but it also distends the surrounding walls of the blood vessel and relieves the pressure on any accumulation of clots or fibrin, and allowing movement thereof toward the drain tube where they collect beneath the distended bowed blades or wires 10. Upon release 50 of compression such masses of material are caught beneath the blades 10 and upon retraction of the rod or stem 7 such clots and masses of 55 stringy substance are withdrawn into the tube from which they will pass through the discharge branch 2, leaving the inlet orifices 4 and 6 of the tube unobstructed. The expandable head 9 upon the reciprocatory rod thus serves a threefold purpose, of clearing the lateral slots, distending the 60 walls of the vein to release accumulated material and positively grasping the material for retractive movement into and through the tube, thus 65 insuring a free drainage outlet.

For purpose of limiting expansion of the flexible head 9 and preventing undue distention of the blood vessel about the tube, the rod or stem 7 may be continued within the group of flexible members 10 comprising the expandable 70 head 9 and terminated at a point in spaced relation with the thrust head 11, as is indicated at 7a. As the stem or rod is pressed inwardly subsequently to the contact of the thrust head 11 against the annular abutment 5 of the tube, the members 10 are flexed or bent outwardly

through the slots 6 until the extremity of the rod extension 7a contacts the inner side of the thrust head 11, thereby arresting the advance movement of the rod and preventing further flexing of the members 10. By making the rod extension 7a of different length the degree of expansion may be correspondingly varied. 5

To facilitate the drainage flow, continuations 6a of the longitudinal slots 6 are provided rearwardly thereof and separated by intermediate 10 bridging portions 6b which serve to stiffen and strengthen the slotted portion of the tube. The flexible blades 10 are preferably sufficiently long to extend throughout the combined length of the main slots 6 and extension slots 6a. Such increased length also increases the flexibility of the members 10 which as they are expanded through the main slots 6 by their engagement with the ends 6b thereof are induced to assume a substantially compound curvature by which 15 their rear portions are contracted more closely about the rod within the limits of the slot extensions 6a, thereby permitting free ingress of fluids therethrough.

From the above description it will be apparent 25 that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more 35 or less specific as to structural features, it is to be understood that the invention is not limited to the specific features shown, but that the means and construction herein disclosed comprise the preferred form of several modes of 40 putting the invention into effect, and the invention is therefore claimed in any of its forms or modifications within the legitimate and valid scope of the appended claims.

Having thus described my invention, I claim: 45

1. An instrument for insertion in a restricted passage including an elongated tubular conduit having longitudinal parallel slots adjacent its end, a reciprocatory rod extending within the tubular conduit, an expandable head carried by the rod comprising a group of flexible members 50 collectively connected at one end to the rod and collectively connected at their opposite end to a contact head, an abutment surface on the tubular conduit engaged by said contact head upon axial movement of the head under influence of the rod, said head being subject to axial compression by further movement of the rod whereby the flexible members are bowed outwardly through the longitudinal slots in the tubular 60 conduit.

2. An instrument for insertion in a restricted passage including a tubular conduit having lateral openings therein, a reciprocatory rod extending within the tubular conduit, a head carried by the rod, an abutment surface on the tubular conduit with which the head has thrust engagement upon axial movement of the rod in one direction, said head being deformable upon continued pressure exerted through said rod 70 whereby the head is caused to expand beyond the confines of the tubular conduit through the lateral openings thereof.

3. An instrument for insertion in a restricted passage including a tubular conduit having lat- 75

eral openings therein, a reciprocatory rod extending within the tubular conduit, a thrust bearing within the tubular conduit limiting the advancement of the rod, and a plurality of flexible members carried by the rod and bowed through the lateral openings of the tubular conduit under influence of thrust pressure upon said rod.

4. An instrument for insertion in a restricted 10 passage including a tubular conduit having lateral openings therein, a reciprocatory rod extending within the tubular conduit, an expandable head for said rod, a thrust bearing within the tubular conduit engaged by the head of the 15 rod before the rod reaches the limit of its range of movement whereby the rod is capable of a limited additional movement by which the expandable head is subjected to axial compression and resulting radial expansion through the lateral 20 opening of the tubular conduit, and means for limiting such additional movement of the rod.

5. A drainage tube for embalmers' use including a tubular conduit having lateral openings therein 25 adapted to be removably inserted into a human body, a reciprocatory rod extending within the tubular conduit, and spring means carried by the rod adapted to be expanded through the lateral openings by manipulation of the rod.

30 6. In an instrument for introduction into a restricted passage, a tube having a lateral opening therein, a bowable member confined within the tube when in untensioned condition, and means for flexing the bowable member into a bight 35 formation protruding beyond the confines of the tube through the lateral opening thereof.

7. In an instrument for introduction into a restricted passage, a tubular conduit having a plurality of lateral openings adjacent to one end 40 thereof, a cage like body of flexible members interconnected at their opposite ends normally confined within the tubular conduit, and means for axially compressing the said body to effect flexure of the component members beyond the 45 confines of the tubular conduit through the lateral openings thereof.

8. In an instrument for introduction into a restricted passage, a tubular conduit having lateral 50 openings adjacent to one end thereof, and snare means normally confined within the conduit and operable through the lateral openings thereof into grasping engagement with adjacent material to draw such material into the tube.

9. An instrument for insertion within a restricted 55 passage including a tubular conduit having lateral openings therein, a reciprocatory rod extending within the conduit, and material grasping means projectable through the lateral openings in the conduit for drawing adjacent material into the tube by the manipulation of said rod.

10. An instrument for embalmers use adapted 60 for insertion within a restricted passage in a human body including a tubular conduit having lateral openings therein, a reciprocatory rod extending within the conduit, and an expandable and contractable body normally contained within the conduit and expandable laterally therebeyond by manipulation of said rod to distend the passage about the conduit.

70 11. In a drainage tube for embalmers' use for 75 draining veins, the combination with a tubular member having longitudinal slots in its peripheral wall insertable through an opening into a human body, of a reciprocatory rod therein, an expandable head carried on said rod and normally with-

in the tube and means for expanding such head through the slots by manipulation of the rod.

12. A drainage instrument including an elongated tube having lateral openings therein, a reciprocatory stem extending therein and snare members carried by the rod and capable of projection through the lateral openings into grasp engagement with adjacent material for drawing such material into the tube by manipulation of the rod.

10 13. In an instrument of the character described, a tubular member having longitudinal successions of slots circumferentially spaced adjacent to one end of the tube, an expandable and contractable head insertable within the tube, including a plurality of radially extensible members to be brought into registry with certain of the slots and expanded therethrough beyond the periphery of the tube, and means for effecting simultaneous contraction of a continuing portion of 20 said head contiguous to other slots of said tube.

14. In an instrument of the character described, a tubular member having parallel longitudinal circumferentially spaced slots adjacent to one end thereof, and an expandable and contractable head 25 insertable therein, including a plurality of flexible parallel members adapted to bend into substantially compound curvilinear form under longitudinal compression with the outwardly convex portions thereof bowed through the slots of the tubular member, and means for subjecting said head to longitudinal compression within the tube.

30 15. An instrument of the character described including an elongated tubular member, having a lateral opening adjacent to one end thereof, an expandable body capable of introduction through the tubular member, and means operable through the interior of the tube for controlling the expansion of the body beyond the confines of the tube 35 through the lateral opening for distending the adjacent walls of a restricted passage in which the tubular member has been introduced.

40 16. An instrument of the character described, including an elongated tubular member having therein a lateral opening adjacent to its end, 45 a reciprocatory rod extending therein, an expandable head carried by the rod and normally within the tubular member and subject to distention laterally beyond the confines of the tubular member through the lateral opening therein, the degree of such distention being controlled 50 by the relative longitudinal movement of the tubular member and rod.

55 17. An instrument of the character described, including an elongated tubular member open at its extremity and having a lateral opening adjacent to such open extremity, a reciprocatory rod extending within the tubular member a head carried by the rod, for axial movement of one relative to the other, a seat within the open end 60 of the tubular member upon which the head abuts and a bowable member connecting the head and rod and subject to distortion through the lateral opening in the tubular member under movement of the rod relative to the head while 65 the latter is in abutting engagement with the seat.

70 18. An instrument of the character described including an elongated tubular member having a plurality of longitudinal slots therein, a rod 70 extending within the tubular member, an assembly of bowable members carried by the rod, a stop within the tubular member against which the bowable members may abut at one end, the opposite end of the bowable members being con- 75

nected with the rod whereby upon thrust pressure of the bowable members against the stop incident to longitudinal pressure upon the rod, the bowable members will be laterally distended 5 through the longitudinal slots of said tubular member.

19. An instrument of the character described including an elongated tubular member having a plurality of longitudinal slots therein, a rotatable rod extending within the tubular member, an expansible and contractable assembly of bowable members carried by the rod, said assembly of bowable members being revoluble within the tubular member about the axis there- 10 of into and out of registry with the longitudinal slots through which they are distendable when brought into registry therewith by manipulation of the rod.

20. An instrument of the character described including an elongated tubular member, having an open end and having a plurality of longitudinal slots adjacent to such open end, an internal annular abutment seat contiguous to the 5 open end of the tubular member, a rod extending within the tubular member, an assembly of bowable members, and a tapered guide head connected with the rod by said assembly of bowable members, said head being adapted to abut 10 the annular seat and project beyond the end of the tubular member upon axial thrust movement of the rod and upon further thrust movement of the rod said bowable members being subject to distension laterally beyond the con- 15 fines of the tubular member through the longitudinal slots thereof.

WARD R. SMITH.
